DESIGN FOR A PORTABLE THEATRICAL STAGE

Albert A. Ostrander, Pleasantville, and
Lee A. Kalech, New York, N. Y.

Application March 7, 1946, Serial No. 127,186

Term of patent 3½ years

(Cl. D13—1(2))

To all whom it may concern:

Be it known that we, Lee A. Kalech and Albert A. Ostrander, both citizens of the United States of America, and residing respectively at New York city, in the county and State of New York, and Pleasantville, in the county of Westchester and State of New York, have invented a new, original, and ornamental Design for a Portable Theatrical Stage, of which the following is a specification, reference being had to the accompanying drawing, forming a part thereof.

Fig. 1 is a perspective view of a portable theatrical stage, showing our new design.

Fig. 2 is a plan view of the stage, taken on line 2—2 of Fig. 1.

We claim:

The ornamental design for a portable theatrical stage, substantially as shown.

ALBERT A. OSTRANDER.
LEE A. KALECH.
